United States Patent

Des. 240,151
Patented June 1, 1976

240,151

TOY STAGE

Albert Stubbmann, Franklin Lakes, N.J., assignor to Kohner, Inc., New York, N.Y.

Filed Oct. 7, 1974, Ser. No. 512,570

Term of patent 14 years

Int. Cl. D21—01

U.S. Cl. D34—15 R

FIG. 1.

FIG. 2.

FIG. 3.

FIG. 4.

FIG. 5.

FIG. 1 is a perspective view of a toy stage showing my new design;

FIG. 2 is a front elevational view thereof;

FIG. 3 is a rear elevational view thereof;

FIG. 4 is a side elevational view thereof; and

FIG. 5 is a bottom plan view thereof.

I claim:

The ornamental design for a toy stage, as shown.
